UNITED STATES PATENT OFFICE.

WILLIAM G. RAGSDALE, OF JAMESTOWN, NORTH CAROLINA.

BOBBIN-HOLDER.

No. 867,532.

Specification of Letters Patent.

Patented Oct. 1, 1907.

Application filed April 13, 1907. Serial No. 368,080.

To all whom it may concern:

Be it known that I, WILLIAM G. RAGSDALE, a citizen of the United States of America, residing in Jamestown, in the county of Guilford and State of North Carolina, have invented certain new and useful Improvements in Bobbin-Holders, of which the following is a specification.

My invention relates to that class of bobbin holders which are employed in yarn spooling machines to support bobbins during the unwinding of yarn therefrom in which provision is made for holding the bobbins loosely so that they may rotate freely as the yarn is unwound, and in which provision is also made for discharging empty bobbins to give place to full ones. Heretofore the full bobbin has been made to lie on a stationary or fixed rest or pan and has been held therein by loosely hanging side guards or frames carried by a pivoted arm projecting from a supporting frame. As the yarn is unwound and the bobbin grows smaller in diameter the guards approach each other and bear on the opposite sides of the bobbin so as to hold it in place on its rest. When the yarn is all unwound from the bobbin, the pivoted arm is turned in such manner as to quickly move the empty bobbin sidewise from its rest and then the arm is turned back to its former position and a full bobbin is placed on the rest between the guards.

The primary object of my invention is to provide means whereby the act of discharging a spent bobbin from its rest will bring into place a reserve or full bobbin. In this way considerable time is saved in keeping the bobbin holders supplied and the output of the machine is correspondingly increased.

In carrying out my invention, I provide a single fixed rest or trough and two sets of side guards which are loosely connected to opposite sides of a spindle which is adapted to turn about its longitudinal axis. While one bobbin is held in its rest and the yarn is being unwound therefrom, another full bobbin, or reserve bobbin, is held between another set of side guards on the opposite side of the spindle, and when the spindle is turned to cause one set of side guards to discharge the empty bobbin from its rest, the other set of guards carry the reserve bobbin onto the fixed rest or support and the loose end of the yarn may be immediately attached to the spooling mechanism. The reserve bobbins can be placed in position while all the other bobbins are feeding to the spool mechanism and when the attendant has nothing else to do. While the bobbin is feeding yarn to the spooling mechanism, the spindle, which supports the side guards, is locked in place, but the locking mechanism is such that it can be easily loosened to permit the spindle to be turned when the attendant so desires. In order to

hold the loose end of the yarn from the reserve bobbin, 55 the outer end of the spindle is notched and slotted for this purpose.

In the accompanying drawings,—Figure 1 shows a side elevation of my improved bobbin holder with a bobbin in position to feed to the spooling mechanism, 60 Fig. 2 is a view in elevation of the outer end of the holder with full bobbins therein. Fig. 3 is a perspective view of the same. Fig. 4 is a perspective view showing 65 the manner in which an empty bobbin is discharged and a full bobbin is made to take its place. Fig. 5 is a detail view on an enlarged scale and in section showing the manner in which the spindle is connected with its supporting frame. Fig. 6 is a perspective view of one 70 of the blocks carried by the spindle to which the side guards are connected. Figs. 7, 8 and 9 show parts of the devices for connecting the spindle to its supporting frame.

The supporting frame, A, is provided with a clamping device, A', by means of which it may be secured to the bobbin-holder-supporting-bar, B, of a spooling machine in the usual way. The fixed rest, C, for the bobbin is as usual adjustably connected at c with the frame, A. This fixed rest is in general of ordinary construction except that it is prolonged laterally on one side, c', for a purpose hereinafter described. The supporting frame is mainly circular in form and centrally through the circular portion of the frame extends a spindle, D, which projects out beyond the outer end of 85 the front rest, C, and is formed with a notch, d, and a slot, d', to receive the loose end of the yarn from the reserve bobbin. The spindle also projects beyond the rear side of the frame, A, and while it is adapted to turn about its own axis in this frame, it is provided with 90 devices which lock it securely while yarn is being fed to the spooling machine. For this purpose the spindle is preferably shouldered at, e, and bears against a boss, f, on the front side of the frame, A, and the reduced circular portion of the spindle is threaded at its outer end 95 and receives nuts, G, between which and a sliding block, H, is interposed a coiled spring, I. The block, H, is adapted to bear against the outer end of a boss, f', on the back side of the frame, A, and is normally pressed into engagement therewith by the spring, I, which also 100 tends to press the shoulder, e, against the boss, f. The front side of the block, H, is provided with recesses, h, and a pin, K, passing through the recesses and through the spindle prevents the block, H, from turning on the spindle but allows it to move endwise thereon. Lugs, 105 L, project rearwardly from the boss, f', on opposite sides of the spindle and are adapted to enter the recesses, h. When so entered the block cannot turn

relatively to the frame, A, and therefore the spindle is prevented from turning. The walls of the recesses, h , are, however, so formed that the lugs, L, may be made to leave the recesses, h , when the spindle is turned to the right by the attendant. It will be observed that the walls, h' , of the recesses are straight, while the walls, h^2 , are curved or inclined. This construction affords cam surfaces so that when the spindle is turned by the attendant to the right the lugs 5 will ride on the inclined surfaces and cause the sliding block to move backwards until the lugs are disengaged, and then the spindle can turn freely through an arc of 180 degrees when the block will again spring forward, the lugs will be engaged and the spindle 10 forward, the lugs will be engaged and the spindle 15 locked. This lock acts positively against all accidental rotation of the spindle, but it may be easily disengaged by the attendant when so desired.

I employ what is known in the art as side guards for the bobbins and which are of the usual construction 20 and operate in the usual way except that I employ duplicate sets of guards, whereas before only one set has been used. Each set of guards comprises wire frames, M, which are pivotally connected with their supports in such manner as to have a certain freedom 25 of movement but which movement is limited. In my bobbin-holder the side guards are pivotally connected with the centrally arranged spindle, D. For this purpose the spindle is provided with blocks, N, which are formed with recesses, n , into which the ends of the 30 guards extend and the walls of which limit the swinging movement of the guards in such manner that, while permitting the guards to spread apart or open in order to receive or to drop a bobbin, they are not permitted to spread to too great an extent.

35 As shown in Figs. 1, 2 and 3 a full bobbin, X, lies in its fixed rest, C, and is held in place by the guards, M, in such position as to supply yarn to the spooling mechanism. These figures of the drawings also show a reserve bobbin, X', held in similar guards immediately 40 above the bobbin, X, on the opposite side of the spindle, D. x , indicates the yarn from the bobbin, X, leading to spooling mechanism, while x' , indicates the loose end of the yarn from the bobbin, X', which is held in the outer end of the spindle in convenient 45 position to be taken hold of by the attendant when desired. As soon as the yarn has all been drawn from the bobbin, X, the attendant by merely turning the spindle, D, to the right, may eject the empty bobbin, indicated at Y in Fig. 4, and in so doing will bring the 50 reserve bobbin, X', into feeding position on the fixed rest, X. It will be observed that the portion, c' , of the rest, C, is prolonged in such manner as to meet the reserve bobbin as it descends and guide it into feeding position on the rest. Were it not for this portion, c' , the reserve bobbin would fall out of the guards, M. 55 The opposite side of the rest, however, is not provided with a portion similar to c' , so that when the spindle

is turned the empty bobbin will drop out into a suitable receptacle. It will be understood that the reserve bobbins may be placed in position while the other 60 bobbins are feeding to the spooling machine and when the attendant is not otherwise engaged. In this way much valuable time is saved and the output of the machine is correspondingly increased.

I have shown the best way now known to me of carrying out my invention, but I believe that I am the first to provide a bobbin holder with means for supporting a reserve bobbin which is brought into feeding position in the holder when an empty bobbin is ejected. I therefore do not wish to be limited to the details of 70 construction or the particular construction of apparatus illustrated and described.

I claim as my invention:—

1. A bobbin-holder having a fixed rest to hold a bobbin in feeding position while the yarn is being unwound 75 therefrom, means for ejecting a spent bobbin, and means for supporting a reserve bobbin in the holder.

2. A bobbin-holder having a fixed rest for holding a bobbin in feeding position while the yarn is being unwound 80 therefrom, means for ejecting an empty bobbin from its rest, and means for simultaneously feeding a reserve bobbin to feeding position in the rest.

3. A bobbin-holder provided with a fixed rest, duplicate sets of side guards for a bobbin while feeding and for a 85 reserve bobbin, and means for moving one set of guards from feeding position on the rest and simultaneously bringing the other set of guards into feeding position.

4. A bobbin-holder comprising a fixed rest, a spindle mounted to turn over the rest and duplicate sets of side 90 guards carried by the spindle for supporting a bobbin in feeding position and a reserve bobbin.

5. A bobbin-holder provided with a fixed rest having a laterally projecting extension on one side, a spindle mounted to turn above the rest and duplicate sets of side 95 guards carried by the spindle for holding one bobbin in feeding position and a reserve bobbin.

6. A bobbin-holder provided with means for holding a bobbin in feeding position while the yarn is being unwound therefrom and a reserve bobbin and devices for moving the holding means to eject an empty bobbin and to 100 bring the reserve bobbin into feeding position and hold it there.

7. A bobbin-holder comprising a supporting frame, a spindle having yielding locking devices connecting it with the frame, a fixed rest and duplicate sets of side guards 105 carried by the spindle for holding one bobbin in feeding position and a reserve bobbin.

8. A bobbin-holder comprising a supporting frame having rearwardly projecting lugs, a spindle carrying a block 110 sliding longitudinally on the spindle and formed with recesses engaged by the lugs, means for yieldingly pressing the sliding block into engagement with the lugs, and bobbin-supporting means carried by the spindle.

9. A bobbin-holder comprising a supporting frame, a spindle mounted to turn in the frame and formed with a slot at its outer end to receive the loose end of yarn, and 115 duplicate sets of side guards for holding a bobbin in feeding position and a reserve bobbin.

In testimony whereof, I have hereunto subscribed my name.

WILLIAM G. RAGSDALE.
